[57] CLAIM

The ornamental design for call management device, as shown and described.

DESCRIPTION

FIG. 1 is a perspective view showing the front of the call management device in accordance with the present invention;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof;

FIG. 7 is a top plan view thereof;

FIG. 8 is a perspective view of a second embodiment of the call management device of FIG. 1;

FIG. 9 is a front elevational view of the embodiment shown in FIG. 8;

FIG. 10 is a rear elevational view of the embodiment shown in FIG. 8;

FIG. 11 is a right side elevational view of the embodiment shown in FIG. 8;

FIG. 12 is a left side elevational view of the embodiment shown in FIG. 8;

FIG. 13 is a top plan view of the embodiment shown in FIG. 8;

FIG. 14 is a bottom plan view of the embodiment shown in FIG. 8; and,

FIG. 15 is a perspective view of the call management device with the stand separated therefrom for convenience of illustration.
